UNITED STATES PATENT OFFICE.

SIMON B. HESS, OF NEW YORK, N. Y.

ELECTRICAL RELAY.

1,188,652.

Specification of Letters Patent. Patented June 27, 1916.

Application filed July 8, 1914. Serial No. 849,703.

To all whom it may concern:

Be it known that I, SIMON B. HESS, a citizen of the United States of America, and resident of the borough of Manhattan, 5 in the county of New York and State of New York, have invented certain new and useful Improvements in Electrical Relays, of which the following is a specification.

This invention relates broadly to improvements in electrical devices, and more particularly aims to produce a novel and improved form of relay of a simple, sturdy and reliable construction.

It is an object of this invention to provide 15 a relay of improved construction, wherein there will be eliminated to a greater degree than heretofore the faults common to such devices.

Other objects and aims of the invention, 20 more or less broad than those stated above, together with the advantages inherent, will be in part obvious and in part specifically referred to in the course of the following description of the elements, combinations, 25 arrangements of parts, and applications of principles constituting the invention; and the scope of protection contemplated will appear from the claims.

Referring now to the accompanying drawings, 30 which are to be taken as a part of this specification, and wherein two embodiments, of the many various embodiments possible of illustration, are disclosed as being at present preferred; Figure 1 is a composite view, wherein one embodiment is shown in perspective and with certain of the parts partially broken away, and wherein the circuits illustratively associated therewith are diagrammatically disclosed; Fig. 2 is a view 35 similar to Fig. 1, but showing another embodiment and its associated circuits; and Fig. 3 is a perspective view showing a detail of construction characteristic of both the present embodiments.

40 Similar reference characters refer to similar parts throughout the several views of the drawings.

Referring now particularly to the embodiment disclosed in Fig. 1, and deferring 45 for a moment a description of the various circuits shown in connection with said embodiment, said embodiment is disclosed as including a cruciform bed-plate 4, the termini of one arm thereof including in-

tegral upstanding standards 4' and each 55 of the termini of the other arm thereof including a boss 4''. Each standard 4' has mounted upon the same a cross-bar 5, one of the cross-bars supporting electromagnets 6 and the other cross-bar supporting electromagnets 7. Each boss 4'' is tapped for the reception of a pivot-screw 8, said screws serving pivotally to mount the armature 9. Armature 9 is provided with a depending stud 9', to the lower terminus of which stud 65 is attached a bow-spring 10 intermediate the length of the latter. The armature has affixed thereto a plate 11. Upon this plate is fixedly mounted a female contact 12 and an offset stud 11' adapted to support the up- 70 standing contact 13. Female contact 12 is preferably constructed of some resilient metal (and preferably one of high conductivity, such as silver), whereby there may be established the spring-jaws 12'.

75 Rigidly mounted upon bed-plate 4 but insulated therefrom is a square pillar 14 carrying at its top a binding post 15. Offset from said pillar is a bracket 16, through which is threaded an adjusting-screw 17. Said adjusting screw is provided with an end-stud which, as shown in Fig. 3, is adapted to enter a recess formed longitudinally of a slide-shaft 18. Said slide-shaft is transversely slotted as disclosed in said Fig. 80 3 and the end stud carries a pin, similarly disclosed, to coöperate with said slot. The slide-shaft is horizontally movable transversely of pillar 14; but it is provided with a key 18' as shown in Fig. 3 which coöperates 85 with a suitable key-way formed in pillar 14. Said slide-shaft at its end which is removed from adjusting screw 17 carries a male contact 19 which is provided with a V-shaped face-plate 19'. This face-plate could also 90 be constructed of any suitable material of a high conductivity, such as silver. It may here be stated that male contact 19 is adapted to coöperate, predeterminedly and as hereinafter described, with female contact 100 12 and more particularly with the spring jaws or leaves 12' of the latter. Pillar 14, below bracket 16, is horizontally threaded for the accommodation of an adjusting-screw 21, adapted for use in adjusting bow-spring 10. Rigidly mounted also upon bed-plate 4 but insulated therefrom is a square pillar 22 carrying at its top a binding post 105

23. Offset from said pillar is a bracket 24, through which is threaded an adjusting-screw 25. Said adjusting-screw is provided with an end-stud similar to the end-stud 5 carried by adjusting screw 17; and the end-stud of adjusting screw 25 is adapted to enter a recess formed within a slide-shaft 26 similar to slide-shaft 18, said recess formed in slide-shaft 26 being similar to the recess 10 (see Fig. 3) formed in slide-shaft 18. Slide-shaft 26 is slotted similarly to the slotting of slide-shaft 18, and the end-stud of slide-shaft 26 carries a suitable pin adapted to co-operate with the slot formed in slide-shaft 15 26. Slide-shaft 26 is horizontally movable transversely of pillar 22; but it is provided with a key 26' as shown in Fig. 1 which co-operates with a suitable key-way formed in pillar 22. Said slide-shaft is provided with 20 a squared end upon which are fixedly mounted the coöperant spring members adapted to establish the female contact 27. The members which constitute the contact 27 could also be constructed of any suitable 25 metal of a high conductivity, such as silver. It may here be stated that female contact 27 is adapted to coöperate, predeterminedly and as hereinafter described, with the contact 13 carried by armature 9. Pillar 22, be- 30 low bracket 24, is horizontally threaded for the accommodation of an adjusting-screw 28, adapted for use in adjusting bow- spring 10.

Before proceeding with a description of 35 the operation of the embodiment just described, a consideration of the illustratively elementary wiring systems and associated parts of which the relay is disclosed as constituting a component, will be advantageous. 40 The reference numeral 29 indicates a source of electro-motive force adapted normally, on account of the presence of the properly designed resistance 38 located in a shunt 37' arranged across a fire-alarm 45 box 33 of the usual type, to pass practically all of its current through a single circuit including a wire 29', a wire 30, an electro-mechanical gong 31, a wire 32, fire-alarm box 33, a wire 34, electromagnets 7, and wire 50 35 to return to the source of supply 29. Another circuit may be traced as including the shunt 37', said shunt comprising a wire 37, said resistance 38, a wire 39, electromagnets 6, and a wire 40. In addition to the 55 two circuits just described, there are shown a plurality of auxiliary circuits which have interposed therein a common source of current supply 41. An alarm circuit is formed leading from said source 41 to a bell 44 and 60 includes wires 42 and 42'; a wire 43 leads from said bell 44 to the binding post 15; and a wire 45 leads from pivot-screw 8 back to the source 41. The other auxiliary circuit is a warning circuit or signal circuit, and 65 includes the wire 42, a bell 46, a wire 47

leading to the binding post 23, and the wire 45 leading from pivot-screw 8 back to the source 41.

It may be well at this point to define the circuit which includes the gong 31 (which 70 gong would preferably be located on a particular floor) as the "protective or fire-alarm circuit"; to define the circuit which includes the resistance 38 as the "circuit for indirectly bringing about the operation of bell 44"; to define the circuit which includes 75 said bell 44 (which bell would preferably be located at alarm-headquarters) as the "circuit for directly operating bell 44", and to define the circuit which includes the bell 46 80 (which bell would also be preferably located at alarm-headquarters) as the "circuit for indicating a failure of source of supply 29. Now, as aforesaid, the protective or fire-alarm circuit, due to the presence as 85 aforesaid of shunt 37' and resistance 38, normally allows the deenergization of electromagnets 6, but energizes electromagnets 7, and contact 13 is then located as shown in 90 broken lines at 13' in Fig. 1, thus maintaining open both the bell-44 circuit and the bell-46 circuit. (Bell 44 and bell 46 are 95 preferably so designed that each has a characteristic and individually recognizable timbre). Upon a failure of said protective or fire-alarm circuit, or upon a manual release of the circuit opening means located in fire-alarm box 33 which means usually consist of an intermittently operating circuit breaker, the electromechanical gong 31 is actuated a 100 predetermined number of times (say to indicate the particular floor of the building upon which the fire occurs). Simultaneously, due to the consequent failure of the protective or fire-alarm circuit, and the extra surge of 105 current through the circuit for indirectly bringing about the operation of bell 44 (which circuit includes as aforesaid the resistance 38), electromagnets 6 are energized. This brings together contacts 12 and 19, 110 wedging the latter tightly between the spring jaws 12' of the former, at the same instant causing a snapping of contact 13 from its just-mentioned location 13' past contact 27 to take up its location 13'' shown 115 in Fig. 1, thereafter still to maintain open the bell-46 circuit. These operations result in a closing of bell-44 circuit and the giving of an alarm at fire-alarm headquarters. Upon a failure of the main source 29, and a 120 consequent deenergization of both electromagnets 6 and electromagnets 7 leaving the armature unattracted, (irrespective of whether contact 13 was just previously occupying the location 13' or the location 13'' 125 illustrated in Fig. 1), the predetermined tension of bow-spring 10, due to its adjustment by means of adjusting-screws 21 and 28, constitutes means for resiliently moving armature 9 to an intermediate position such 130

that contacts 13 and 27 become coöperant. Upon this occurring, the bell-46 circuit is closed, and gives said fire-alarm headquarters immediate notice of the failure of said source 29.

The possibilities of this embodiment of the invention having been made apparent by the foregoing, certain of the advantages inherent in the relay disclosed in Fig. 1 may now be mentioned. In the first place, attention is directed to the form of contact 19 which establishes a wedging result in connection with contact 12, whereby it is inconceivable that said contacts may ever fail to make a certain connection and one of gradually increasing and comparatively great final area. In the second place, attention is directed to the form and characteristics of contact 27 whereby the contact 13 may be disposed at a point in either direction relatively of said contact 27 and longitudinally of slide-shaft 26, at each of which points said contact 13 will be removed from connection with contact 27, and from each of which points said contact 13 may be spring-urged to advance toward said contact 27 to make connection therewith upon a failure of both sets of electromagnets. Attention is also directed to the means which are provided for longitudinally and with great exactitude adjusting slide-shafts 18 and 26, without transmitting to them any undesirable motion similar to the rotative functioning of adjusting-screws 17 and 25.

Referring now particularly to the embodiment of Fig. 2, the same is shown as including a cruciform bed-plate 48, the termini of one arm thereof including integral upstanding standards 48' and each of the termini of the other arm thereof including a boss 48''. Each standard 48' has mounted upon the same a cross-bar 49, one of the cross-bars supporting electro-magnets 50 and the other cross-bar supporting electro-magnets 51. Each boss 48'' is tapped for the reception of a pivot-screw 52, said screw serving pivotally to mount the armature 53. Armature 53 is provided with a depending stud 53', to the lower terminus of which a stud is attached a leaf-spring 54. The armature has affixed thereto a plate 55. Upon this plate is fixedly mounted a female contact 56, which is preferably constructed of some resilient metal (and preferably one of high conductivity, such as silver), whereby there may be established the spring-jaws 56'.

Rigidly mounted upon bed-plate 48 but insulated therefrom is a square pillar 57 carrying at its top a binding-post 58. Offset from said pillar is a bracket 59, through which is threaded an adjusting screw 60. Said adjusting-screw is provided with an end-stud similar to that shown in Fig. 3 in connection with adjusting-screw 17; and which end-stud of adjusting screw 17 is

adapted to enter a recess formed longitudinally of a slide-shaft 61, said recess and slide-shaft being respectively similar to the recess and slide-shaft 18 disclosed in Fig. 3. The end-stud of adjusting-screw 60 is provided with a pin similar to the pin shown in Fig. 3 as being carried by the end-stud of adjusting-screw 17, and the pin of adjusting screw 60 coöperates with a slot formed in slide-shaft 61 and similar to the slot shown in said Fig. 3 as being formed in slide-shaft 18. Slide-shaft 61 is horizontally movable transversely of pillar 57; and it is provided with a key similar to the key 18' (see Fig. 3) which coöperates with a suitable key-way formed in pillar 57. Said slide-shaft 61 at its end which is removed from adjusting-screw 60 carries a male contact 62 which is provided with a V-shaped face-plate 63. This face-plate could also be constructed of any suitable material of a high conductivity, such as silver. In connection with this embodiment, also, let us first consider the illustratively elementary circuits and parts with which the relay is shown as associated.

The reference numeral 64 indicates a source of supply adapted to pass current through electromagnets 51, a fire-alarm box 65 and an electro-mechanical gong 66. From an auxiliary source of supply 67, a circuit may be traced which passes through electromagnets 50 and a bell 70, said electromagnets and said bell being arranged in parallel; a wire 71 leading to pivot-screw 52 and a wire 69 leading back to the source of supply 67.

The operation of this embodiment, which is characterized by details of construction and general advantages similar to those of the embodiment shown in Fig. 1, should be largely obvious; for it is clear that upon a manual or other actuation of fire-alarm box 65 the electro-mechanical gong 66 will be operated by a breaking of that circuit which was normally energizing electromagnets 51 and consequently maintaining open the bell-70 circuit. Upon this occurring, contact 56 will be spring-urged toward contact 62 to close said bell-70 circuit. Here the novel design of the contacts serves to make the spring-urged movement of contact 56 sufficient to render certain an energization of electromagnets 50, thereby to capacitate the same to cause the wedging relation of the two contacts, upon whose connection the integrity of the energizing circuit of said electromagnets 50 depends, to be more certain and positively maintained. The bell 70, in parallel with the electromagnets last-mentioned, gives a suitable alarm.

Inasmuch as many changes could be made in the above construction, and many apparently widely different embodiments of my invention could be made without departing

from the scope thereof, it is intended that all matter contained in the above description or shown in the accompanying drawings shall be interpreted as illustrative and not 5 in a limiting sense.

It is also to be understood that the language used in the following claims is intended to cover all the generic and specific 10 features of the invention herein described and all statements of the scope of the invention, which, as a matter of language, might be said to fall therebetween.

I claim:—

1. In a device of the class described, in 15 combination, a pair of coöperant contacts one movable relatively of the other, one of the contacts being wedge-shaped and the other being so formed as to establish a recess within which the first-mentioned contact 20 may be electromagnetically wedged, and rotative means adapted to be actuated to adjust said wedge-shaped contact relatively of the other and at the same time to maintain said wedge-shaped contact in line with the 25 breast of said coöperant contact.

2. In a device of the class described, an armature disposed between two electromagnets, in contact with a coöperant contact member, and adapted to be electromagnetically 30 influenced in either of two directions, thereby to open a circuit.

3. In a device of the class described, in 35 combination, a first electromagnet adapted normally to hold an armature in an attracted position, a second electromagnet adapted abnormally to attract said armature upon a decrease of magnetic strength in the electromagnet first mentioned, to close a first circuit in its path of movement while being 40 actuated by said second electromagnet.

4. In a device of the class described, in 45 combination, a first electromagnet adapted normally to hold an armature in an attracted position, a second electromagnet adapted abnormally to attract said armature upon a decrease of magnetic strength in the electromagnet first mentioned, to close a first 50 circuit in its path of movement while being actuated by said second electromagnet, and to close a second circuit while in engagement with the second electromagnet and adapted to be automatically restored to normal upon a change of magnetic influence to normal.

5. In a device of the class described, in 55 combination, a first electromagnet adapted normally to hold an armature in an attracted position with its associated contact member within the enlarged resilient recess of its coöperant contact member but not in engagement therewith, a second electromagnet adapted abnormally to attract said armature upon a decrease of magnetic strength in the electromagnet first mentioned, to 60 close a first circuit in its path of movement

while being actuated by said second electromagnet, and to close a second circuit while in engagement with the second electromagnet, and adapted to make a second contact to again close said first circuit in its path 70 of movement in automatically restoring to normal upon a change of magnetic influence to normal.

6. In a device of the class described, in 75 combination, two electromagnets, one disposed relatively opposite the other, and means for energizing both, from one source of energy, two polepieces, a neutral armature and trunnion mounted centrally between said electromagnets, adapted to vibrate according to the preponderance of magnetic flux in one or the other of said electromagnets.

7. In a device of the class described, a 80 neutral armature disposed between two series wound electromagnets, movable in either of two directions from a central position, according to the preponderance of magnetic strength in one or the other of said electromagnets.

8. In a device of the class described, in 85 combination, an armature, two contact members associated therewith, one being rigid and L shaped and one being resilient and substantially V shaped in form, a first electromagnet adapted normally to hold said armature in attracted position with its associated rigid contact member within the enlarged resilient recess of one of its coöperant contact members but not in engagement therewith, a second electromagnet and an adjustable triangular contact member associated therewith, said second electromagnet being adapted to attract said armature, to make momentary contact between the 90 rigid contact member and its coöperant resilient contact member to close a circuit, and a permanent contact between the second mentioned contact member, and its coöperant triangular contact member, upon a decrease of magnetic strength in the electromagnet first mentioned.

9. In a device of the class described, in 95 combination, a first electromagnet adapted normally to hold an armature in an attracted position with its associated contact member within the enlarged resilient recess of its coöperant contact member but not in engagement therewith, a second electromagnet adapted abnormally to attract said armature upon a decrease of magnetic strength in the electromagnet first mentioned, to close a first circuit in its path of movement while being actuated by said second electromagnet, and to close a second 100 circuit while in engagement with the second electromagnet and adapted to automatically restore to normal upon a change of magnetic influence to normal.

10. In a device of the class described, in 105

combination, two electromagnets, each comprising a coil serially wound, a pole-piece and yoke, a trunnion pivotally supporting a neutral armature centrally disposed between said electromagnets, and a plurality of contact switch members controllable by said armature according to the preponderance of magnetic influence.

11. In a device of the class described, an 10 adjustable contact member comprising, a bed plate, a pillar mounted thereon, a bracket offset from said pillar, through which is threaded an adjusting screw pro-

vided with an end piece, and a transversely slotted slide shaft having a longitudinally formed recess for said end piece and carrying at its end a wedge shaped contact adapted to be rotatively adjusted without disturbing the alinement of said wedge.

In witness whereof I have hereunto signed 20 my name in the presence of two witnesses.

SIMON B. HESS.

In the presence of—

AUGUSTUS M. HENRY,

GEO. F. MATTUCK.
